UNITED STATES PATENT OFFICE.

GEORGE MICKLE TATUM, OF MEDIA, PENNSYLVANIA.

RUBBER BALL.

1,346,991.

Specification of Letters Patent. Patented July 20, 1920.

Application filed January 22, 1920. Serial No. 353,173.

To all whom it may concern:

Be it known that I, GEORGE M. TATUM, a citizen of the United States, residing at Media, in the county of Delaware and State 5 of Pennsylvania, have invented certain new and useful Improvements in Rubber Balls, of which the following is a specification.

This invention relates to improvements in rubber balls and may also be applied to hollow spheres or globes constructed of any thin or light material such as celluloid for instance and has for its principal object the insertion of a metallic ring in the interior thereof so as to cause the sphere to return 10 to the person who may roll same from him.

Another object of the invention is to provide a sphere having a groove formed internally thereof which is situated to one side of the sphere and adapted to receive 20 a metallic strip so that when the sphere is rolled so that said strip will be in a vertical position it will be seen that weight thereof will turn the sphere to the side to which it is set from the center of the sphere.

Other objects and advantages of my invention will be readily seen by referring to the accompanying specification, claims and drawings, wherein I have disclosed the preferred embodiment of my invention and 30 have particularly set forth the novelty thereof in the appended claims.

In the drawings:—

Figure 1 is a central cross section taken through the ball, and

Fig. 2 is a section taken on the line 2—2 of Fig. 1.

By referring to the accompanying drawing, it will be seen that 1 designates the sphere or ball which may be constructed of any desired light and thin as well as flexible material and I prefer to use rubber for so constructing same. Upon the interior periphery of the sphere 1 I have provided a circular thickened portion 2 which is situated to one side of the center of the sphere 45 for a purpose to be hereinafter set forth.

This thickened portion 2 is provided with a channel for receiving the metallic strip 3. The metallic strip 3 it should be understood

is constructed of material having sufficient 50 weight so that when the sphere is motionless the plane of the circular strip 3 will be horizontal. In order to indicate to the operator of this sphere or ball where the location of the strip 3 lies, I would prefer to have 55 a corresponding strip painted upon the exterior periphery of the sphere. This however is not absolutely necessary as it will be readily understood that when the ball is constructed of rubber or some such similar flexible material the position of the strip 3 may be readily ascertained by the sense of touch.

From the above description it will be seen that the strip 3 is situated so as to be to one side of the center of the sphere so that 65 when same is placed in a vertical position and the ball or sphere rolled, the same will have a tendency to turn to the side upon which is situated the strip 3 and return to the operator. This toy ball may undoubtedly be put to other amusing uses which it is not necessary here to disclose. It will also be understood that I have set forth the preferred embodiment of the invention and that I may make such changes 70 in arrangement and construction as will fall within the scope of the appended claims.

Having thus described my invention what I claim as new is:—

1. An elastic ball of the class described 80 having a metallic strip situated interiorly thereof and means for holding said strip to one side of the center of said ball.

2. A sphere of the class described having a circular thickened portion situated interiorly thereof and provided with a channel running longitudinally thereof, said thickened portion situated to one side of the center of said sphere, and means adapted to be placed in said channel so as to make this 85 portion of the sphere heavier than its other portions.

In testimony whereof I affix my signature in presence of two witnesses.

GEORGE MICKLE TATUM.
